FILAMENT SUPPORT

Ralph C. Shermund, San Francisco, Calif., assignor to Heintz and Kaufman, Ltd., San Francisco, Calif., a corporation of Nevada

Application May 22, 1935, Serial No. 22,723

3 Claims. (Cl. 250—27.5)

My invention relates to a filament support for thermionic tubes and more particularly to a filament support adapted to carry current to a plurality of parallel filaments.

5 Among the objects of my invention are: To provide a two-lead filament support for a plurality of filaments connected in parallel; to provide a two-lead filament support which is adapted to carry a varying number of parallel filaments; and to provide a simple and easily manufactured filament support for energizing parallel filaments.

10 Other objects of my invention will be apparent or will be specifically pointed out in the description forming a part of this specification, but I do not limit myself to the embodiment of the invention here described, as various forms may be adopted within the scope of the claims.

The drawing illustrates a longitudinal view, 15 partly in elevation and partly in perspective, of a preferred embodiment of my invention; and the broad aspects thereof may be more readily understood by reference to a detailed description of the embodiment illustrated.

20 A thermionic tube envelope 1, the size and shape of which is not material to the present invention, is provided with a means for sealing relatively heavy leads therethrough, preferably a stem fused in the usual manner in one end 25 of the envelope and carrying cathode leads 4 sealed through the press 5 thereof. I prefer to use two relatively heavy cathode leads and place between them a spring support rod 6 extending axially through the tube.

30 As I wish to mount a plurality of filaments energized in parallel on the two leads 4 I prefer to bend the leads in several directions, so that they will cooperate to present in a single plane a number of attachment points for the leg ends 35 of inverted V shaped filaments 7. The bights 9 of the filaments are supported by filament springs 10 attached to an upper spring support disc 11 and extending through apertures in the lower filament spring support disc 12, the discs 40 being spaced to allow room for the springs between them, both being solidly attached to the center spring support 6.

45 For purposes of illustration I have shown surrounding the filament assembly an anode 14 supported by anode leads 15 sealed through an upper stem 16. I do not, however, wish to be in any way limited to auxiliary structure, as the anode 14 is shown for purposes of illustration only and the tube may be supplied, in addition to 50 an anode, with various other electrodes, such as

grids or similar structures which are useful when a pure electron discharge is to be controlled, or where the tube is to be used as a grid-controlled arc rectifier.

The essence of the present invention is embodied in the particular manner by which the cathode leads 4 are bent within the tube to provide attachment points preferably in the same horizontal plane for the leg ends of the filament 5 7. The cathode leads 4 are brought for 10 a distance inside the tube parallel to the axis as uprights 17—17. Each of the uprights is then bent to form a horizontal extension 19. These horizontal extensions are preferably parallel and spaced from each other. Each lead 15 20 is then bent downwardly to form vertical legs 20, and thus the two bent leads form attachment elbows 21.

The leads are again bent to pass across and below the horizontal extensions 19 and are again 25 maintained parallel and spaced. The ends of the leads are then bent upwardly to terminate in the plane of the elbows 21 at approximately midway of the extensions 19 and spaced therefrom. Terminals 22—22 will form with elbows 25 21 a rough circle or, more accurately, a hexagon. The leg ends of the filaments are then attached either between a terminus 22 and an elbow 21, or between elbows 21—21, so that each filament 30 will contact first one lead and then the other, thus giving a support for the leg ends of either six V shaped filaments or, with the same structure, by leaving out every other one, three filaments, all operating in parallel. As the filaments 35 operate in parallel all bights 9 are at the same potential and need not be insulated.

Such a structure as has above been described is exceptionally simple and efficient in supplying current to a plurality of filaments. There 40 is good spacing between the leads, and the structure is sufficiently open so that welding points may be easily inserted between the leads in order to weld the filaments to the elbows or to the termini. 45

I claim:

1. In combination, a thermionic tube envelope having an inwardly projecting stem, a single pair of current supply leads sealed through said stem, said leads being bent to form a pair of 50 spaced horizontal extensions, and again bent downwardly to form spaced adjacent elbows, and still again bent each lead to pass under the other, and finally rising to terminate in the plane of said extensions, and a plurality of electron emit- 55

ting filaments bridging said leads and connected thereto in the plane of said extensions.

2. In combination, a thermionic tube envelope having an inwardly projecting stem, a single pair of current supply leads sealed through said stem, said leads being bent to form a pair of spaced horizontal extensions, and again bent downwardly to form spaced adjacent elbows, and still again bent each lead to pass under the other, and finally rising to terminate in the plane of said extensions, and spaced therefrom to form a hexagon with said elbows, and a plurality of filaments connected between adjacent angles of the hexagon thus formed.
- 15 3. In combination, a thermionic tube envelope

having an inwardly projecting stem, a single pair of current supply leads sealed through said stem, said leads being bent to form a pair of spaced horizontal extensions, and again bent downwardly to form spaced adjacent elbows, and still again bent each lead to pass under the other, and finally rising to terminate in the plane of said extensions, and spaced therefrom to form a hexagon with said elbows, a plurality of filaments connected between adjacent angles of the hexagon thus formed, and means for supporting the center of said filaments to position them to roughly describe a cylindrical surface.

RALPH C. SHERMUND. 15
